UNITED STATES PATENT OFFICE.

FRANK O'NEILL, OF TOLEDO, OHIO.

VEHICLE-WHEEL.

1,072,979.

Specification of Letters Patent.

Patented Sept. 9, 1913.

Application filed October 24, 1911. Serial No. 656,479.

To all whom it may concern:

Be it known that I, FRANK O'NEILL, a resident of Toledo, in the county of Lucas and State of Ohio, have invented certain new and useful Improvements in Vehicle-Wheels, of which the following is a specification.

One object of this invention is to provide a resilient wheel wherein the cushioning springs are inclosed and fully protected from dirt and moisture.

A further object is to provide cushioning springs of improved construction which are interposed between relatively movable rim parts in such manner as to insure the greatest efficiency, the construction being such that the springs are very durable and while sufficiently stout to maintain the contour of the wheel under normal conditions 20 they are relatively sensitive in absorbing shocks and jars.

In the accompanying drawings, Figure 1 is a view partly in elevation and partly in section of a portion of a wheel rim and 25 wheel body constructed in accordance with the invention, and Fig. 2 is a view of the same partly in top plan and partly in sectional plan. Figs. 3 and 4 are cross sections, taken on lines 3—3 and 4—4, respectively, of Fig. 1.

The improved rim consists of two ring-like parts which are preferably of channel form and fit one within the other and with the cushioning springs inclosed in the channels. In the adaptation here shown the inner channel consists of the base portion 2 and the opposite channel sides 3, 3'. The outer rim-forming channel, here shown as embracing the inner channel, consists of the tread-carrying base 4, from which projects 35 the integral channel side 5, while secured to base 4 in parallel relation with side 5 is the removable ring-like plate 6 which forms the opposite side of the channel and which is held in place by bolts 7. The outer channel 40 has a working fit over the inner channel so that the channels may move relatively to each other radially of the wheel. The opposite walls 3, 3' of the inner channel are recessed to confine packing 8 which excludes 45 water and dirt from the channel-inclosed space.

Within the channel-inclosed space are the 50 springs 9 of band form, each spring being bent to form the central loop 10, and at opposite sides of this loop are the reversely

disposed loops 11 which merge into the curved portions 12, and extending from the latter are the reversely disposed spring extremities 13 which bear on the inner face of 60 channel base 4.

The central loop 10 of each spring embraces a stud bolt 14 secured in the channel sides 3, 3', the inner extremity of the bolt being threaded into side 3', Fig. 4, the bolt 65 being introduced and removed through an opening it fits in the side 3 when side 6 of the outer channel is removed, this removable channel side also permitting the two channels to be removed and separated, 70 as will be understood.

The springs 9 are introduced through openings 2' in base 2 of the inner channel, and after being brought to position by any suitable means the studs 14 are inserted, and 75 the springs are thus permanently held in place. After all of the springs have been positioned the improved rim is placed on the main body of the wheel, felly 15 of the latter closely fitting within the inner rim part and covering and sealing openings 2' 80 in the base thereof. Lugs 16 projecting from the inner channel are secured to felly 15 by bolts 17.

The invention is not restricted to any particular form of tread. That here shown is in the form of a solid rubber tire 18 which is confined by the clenchers 19 carried by the outer channel.

Each spring is balanced or suspended as 90 it were on its supporting stud 14, and each half of the spring has a free range of movement in both circumferential and radial direction, with the result that they are very elastic and at the same time strong and 95 durable. The condition of the springs may be readily ascertained by removing the channel-side 6, and any spring may be replaced by removing the channel-formed rim from the wheel body to uncover openings 2'. Lubricant may be admitted at 20 to the 100 spring-confining space, insuring easy working of the springs with relation to their supports and to the outer channel which bears thereon.

The construction here shown and described provides for ample play between the rim-forming parts radially of the wheel without admitting either water or dirt to the spring-confining space so that the springs 110 are not retarded by corrosion or accumulation of foreign matter.

I claim:

1. In a wheel, the combination of inner and outer rim-like parts one fitting within the other and with said parts movable relatively to each other radially of the wheel, transverse supports carried by the inner rim part and spaced outwardly from the base of said part toward the outer rim part, and a spring for each of said supports, each 10 spring consisting of a piece of metal having its extremities bearing against the outer rim part and at its center curved to embrace the portion of the support facing the outer rim part and at the opposite sides of its center 15 bent in loop form toward the base of the inner rim part with said loops extending outwardly toward the extremities of the spring which engage the outer rim part.
2. In a wheel, the combination of inner 20 and outer rim-like parts one fitting within the other and with said parts movable relatively to each other radially of the wheel, opposite outwardly extending flanges on the inner rim part, transverse studs spaced outwardly from the base of the inner rim part and secured to said flanges, and springs supported by said studs with the extremities of each spring bearing against the outer rim part, the center of each spring being curved 25 toward the outer rim part to embrace its supporting stud with the portions of the spring at opposite sides of the stud looped toward the base of the inner rim part and with said opposite loops merging into the 30 extremity portions which engage the outer rim part.
3. In a wheel, the combination of inner and outer rim forming members movable relatively to each other radially of the wheel, 35 means holding the relatively movable members in assembled relation with spring inserting openings in the base of the inner member, spring retaining devices within and secured to the inner member inwardly from

said openings, springs held in engagement 45 with the outer rim member by said retaining devices, and a wheel body over which the inner channel member fits with said body closing the spring inserting openings.

4. In a wheel, the combination of inner 50 and outer rim-forming channels one fitting within the other with the channels movable relatively to each other radially of the wheel, a wheel body to which the inner channel is secured and with openings in the base of 55 the inner channel which are covered by the body, springs in the channel-inclosed space adapted to be entered through the openings in the base of the inner channel, supports bridging the inner channel, and springs 60 within the channel-inclosed space, each spring bent to embrace one of the supports with the springs engaging the outer channel and opposing inward movement thereof.

5. In a wheel, the combination of inner 65 and outer rim-forming channels one fitting within the other and with the channels movable relatively to each other radially of the wheel, the outer channel adapted to support a tread and formed with a removable side 70 for placing the outer channel over the inner channel, springs inclosed by the channels and opposing inward movement of the outer channel, studs bridging the inner channel and with each spring bent to embrace one 75 of the studs, the base of the inner channel formed with openings through which the springs are adapted to be inserted, and a wheel body fitting within the channel and to which the latter is secured and closing 80 the base openings therein.

In testimony whereof I affix my signature in presence of two witnesses.

FRANK O'NEILL.
